UNITED STATES PATENT OFFICE.

TOM DICKINSON, OF ACCRINGTON, ENGLAND, ASSIGNOR TO ENTWISLE & KENYON LIMITED, OF ACCRINGTON, ENGLAND.

CARPET SWEeper.

Application filed December 12, 1925, Serial No. 75,104, and in Great Britain April 30, 1925.

This invention relates to carpet sweepers in which the axles upon which the wheels rotate project through holes in the ends of the sweeper case.

5 The axles are carried or supported on springs to permit the user by pressure upon the handle to adjust the position of the brush in the machine in relation to the carpet or surface under operation and to maintain the 10 wheels in contact with the peripheries of the brush pulleys.

Consequent on this movement of the axles the holes in the ends of the case through which they project are of relatively large 15 diameter to permit same. We find that in use these holes become filled with dust and fluff from the interior, retarding or obstructing the free movement of the axles and require frequent clearing or the fluff becomes 20 jammed in the holes preventing the desired movement of the axles and the sweeper from performing its work efficiently.

According to the invention, covers of a flexible or elastic material are fitted over the 25 axle holes, attached to the axle and to the inside of the case, which, while allowing free movement to the axle will prevent loose fluff and dirt from entering the holes from the interior.

30 The invention will be described with reference to the accompanying drawings.

Fig. 1 is a transverse section of sweeper.

Fig. 2 is a sectional plan of same.

Fig. 3 is a front elevation of cover.

35 Fig. 4 is a section of same enlarged showing the cover in position on the sweeper.

The sweeper is of ordinary construction with casing or box A, brush B, wheels C, axles c and springs C¹ carrying the axles c 40 and holes c¹ in the ends of the case through which the axles c project from the inside to the outside of the casing A.

A cover D of flexible or elastic material is fitted over each of the holes c¹ preferably in 45 a recess a on the inside of the wall of the casing and through it the axle passes, the cover being so constructed as to allow free movement to the axle and at the same time prevent loose fluff or dirt passing into or 50 through the holes from the interior.

The cover D comprises a flexible or elastic disc d of canvas, thin sheet rubber or other suitable fabric or flexible material with a central hole provided with an eyelet or rim d¹ of metal or other suitable material to fit 55 closely around the axle c. The outer edge of the disc d is stiffened or strengthened with a ring d² of metal or other suitable material. The diameter of the disc d of flexible material is greater than the diameter of the ring d² so that the flexible material will be loose between the rim d¹ and the ring d² and thus permit of a floating eccentric movement of the central rim or eyelet d¹ in relation to or within the ring d². 60

The axle c passes through the central hole or eyelet d¹ of the flexible cover D, the flexible cover being affixed to the inside of the casing A in a recess a by pegs or screws d³ through the ring d². When fixed in position the centre eyelet d¹ or hole is in alignment with the outer ring d² and the intervening flexible material d is slack allowing freedom to the axle for its adjusting movement. 65

70 What I claim as my invention and desire to protect by Letters Patent is:—

A carpet sweeper of the type referred to having a casing with an end wall, a supporting wheel and an axle of small diameter upon which the wheel rotates, passing 75 through a large hole in said wall, a disc of flexible material formed with a hole in the centre fitted around the axle and through which the axle extends and a supporting ring of stiff material, formed with an aperture 80 substantially larger than the axle and through which the axle extends, around the outer edge of the flexible disc and affixed to the interior side of the end wall of the 85 sweeper case, the diameter of the disc being greater than that of the supporting ring to permit of an eccentric movement of the centre hole in relation to the edge of the flexible disc. 90

95 In testimony whereof I have hereunto set my hand.

TOM DICKINSON.
